UNITED STATES PATENT OFFICE

130,223

DESIGN FOR A TOY BUILDING

Cecil Coleman, Port Chester, N. Y.

Application July 29, 1941, Serial No. 102,537

Term of patent 3½ years

To all whom it may concern:

Be it known that I, Cecil Coleman, a subject of the King of Great Britain, residing at Port Chester, county of Westchester, and State of New York, have invented a new, original, and ornamental Design for a Toy Building, of which the following is a specification, reference being had to the accompanying drawings, forming a part thereof.

Fig. 1 is a front elevational view of a toy building, showing my new design, with the cover in closed position.

Fig. 2 is a top plan view thereof with the cover in closed position.

Fig. 3 is a side view thereof with the cover in closed position.

Fig. 4 is a front elevational view thereof with the cover in open position.

Fig. 5 is a top plan view thereof with the cover in open position.

Fig. 6 is a side view thereof with the cover in open position.

I claim:

The ornamental design for a toy building, as shown.

CECIL COLEMAN.
